FOUNTAIN PEN

Filed May 10, 1928

Inventor:

Robert I. Brons.

၁၃၅

F. V. Winters

Attorney

UNITED STATES PATENT OFFICE.

ROBERT L. BRONG, OF NEW YORK, N. Y.

FOUNTAIN PEN.

Application filed May 10, 1928. Serial No. 276,733.

This invention relates to fountain pens and the improvements are directed to novel and unique means for controlling the flow of a writing fluid therein.

- 5 Primarily the object of the invention resides in the provision of means, in the form of a valve member, adapted to cooperate with certain passageways to check the flow of a writing fluid to the nib or pen portion thereof.
- 10 Another object is to provide specially formed cooperating parts adapted to co-act with said valve member to accomplish the purpose aforesaid.

Still another object of the invention is to provide a valve member normally seating over an orifice in the discharge end of a pen-retaining means, said member being specially formed to permit its convenient reciprocation to effect the opening and closing of said

20 orifice.

A still further object is to provide a pen or nib portion having a depression conforming to the configuration of a portion of said valve member for sealing the passageway 25 communicating with the above orifice.

With these objects in view, together with others which will appear as the description proceeds, the invention resides in the novel formation, combination, and arrangement of 30 parts, all as will be described more fully hereinafter, illustrated in the drawings, and particularly pointed out in the claims.

In said drawings:

Figure 1 is a central longitudinal sectional view of a fountain pen embodying my invention.

Fig. 2 is a fragmentary view illustrating the forward portion of the article in plan, and especially depicting certain slot means arranged in the same.

Fig. 3 is a transverse sectional view taken on the plane of the line 3—3 of Fig. 1.

Fig. 4 is a plan view of the nozzle portion of the article illustrating the discharge orifice and its communicating groove.

Fig. 5 is a side elevation of the nibs or pen portion; and

Fig. 6 is a plan view of the valve member.

Referring now in particular to the accompanying drawing, wherein like characters of reference denote similar parts throughout the several views, let 5 denote the handle portion having a central bore 6 defining a chamber for the reception of a flexible member 7 forming a reservoir for the writing fluid. The forward portion of said handle 5 is shouldered

and threaded, as indicated at 8, for engagement with the reduced portion 9 of the tubular member 10. The separation of these parts permits convenient access to the interior of the pen when it becomes necessary to replace the flexible member 7 or for general cleaning purposes.

Upon inspection of Fig. 1, it will be observed that said tubular member 10 supports a nozzle member 11, the forward end of the latter extending beyond said member 10 for the purpose of supporting the forward end of the nibs or pen portion 12. In the embodiment of the invention, illustrated in the drawing, said ink-retaining flexible member 7 is stretched over the rear portion of said nozzle member 11 and communicates with the axial bore 13 of the latter, the top portion of said nozzle member 11 being longitudinally grooved, as indicated at 14, while the wall between said bore 13 and groove 14 being provided with an orifice 15. Thus the series of passageways, above described, mutually cooperate to permit the passage of the ink from the flexible member 7 to the nibs or pen portion 12. This construction is similar to the ordinary type of fountain pen, and as will presently appear, it is my purpose to provide means whereby the flow of ink through said communicating passages may be conveniently controlled, to the end that danger of leakage may be entirely obviated.

Said means comprises a valve 16 having a ball portion normally seating over said orifice 15 and positively precluding the passage of ink when in said position. In order to permit free and easy manipulation of said valve from the exterior of the article, the thumb-piece 17, rising laterally from the shank portion 18, extends through a slot 19 formed in the tubular member 10, as clearly shown in Fig. 1, and by the simple expedient of retracting said thumb-piece 17, said valve is moved rearwardly to uncover said orifice 15.

As clearly shown in Fig. 3, said groove 14 is arcuate in cross-section and conforms to the contour of the ball portion of said valve and in order to complete the structure, the pen portion 12, see Figs. 1 and 5, is pressed out, adjacent the rear thereof, to define a depression 20, similarly corresponding in cross-section to the upper contour of the ball portion of said valve. This construction will be readily understood upon inspection of Fig. 3. Thus the depression 20 and groove 14 unite to form a passageway substantially conform-

ing to the diameter of said ball portion and providing a convenient area for the reciprocation of said valve.

When the pen is to be filled, said valve member is retracted to expose said orifice 15, whereupon the usual hinged member 21, contacts with member 22 to depress the flexible member 7, and a reverse operation after the nibs are dipped into the ink permits the filling of the pen. Said valve is now returned to the position shown in Fig. 1, and the usual cap covering the nibs placed in position.

From the foregoing it is apparent that said valve member positively precludes the escape 15 of the ink regardless of the position of the fountain pen in the pocket. When writing is to be done, said valve member is retracted, as aforesaid, and in view of the slight resiliency between the ball portion of the valve 20 and the depression form in the nibs, said valve will be held in the retracted position during the use of the article.

While the present is a disclosure of the preferred embodiment of the invention, it is to be understood that the invention is not limited thereto, as various changes in the minor details of construction, proportion and arrangement of parts may be resorted to without departing from the spirit of the invention 30 as defined in the appended claims.

I claim:

1. In a fountain pen, a tubular handle defining a reservoir for ink, a tubular member

having a lateral slot and connected to said handle, a nozzle member carried by said tubular member, having its top face longitudinally grooved and provided with an orifice extending from said groove to the bore of said nozzle member, a pen portion having its rear portion depressed and cooperating with said groove to present a passageway substantially circular in cross-section, and a valve member having a ball portion normally seated over said orifice and having a thumb-piece extending through the slot in said tubular member and adapted to be manipulated to reciprocate said ball portion in said circular passageway to open and close said orifice. 35

2. In a fountain pen, a tubular handle defining a reservoir for ink, a tubular member having a lateral slot and connected to said handle, a nozzle member carried by said tubular member, having its top face longitudinally grooved and provided with an orifice extending from said groove to the bore of 50 said nozzle member, a pen portion carried by said nozzle member and a valve member normally seated over said orifice and having a thumb-piece extending through the slot in said tubular member and adapted to be manipulated to reciprocate said valve in said longitudinal groove in said nozzle member to 55 open and close said orifice. 60

In testimony whereof I affix my signature.

ROBERT I. BRONG.
